UNITED STATES PATENT OFFICE.

JOHN MARDER, OF CHICAGO, ILLINOIS, ASSIGNOR TO MARDER, LUSE & CO., OF SAME PLACE.

DESIGN FOR A FONT OF PRINTING-TYPE.

SPECIFICATION forming part of Design No. 12,557, dated November 1, 1881.

Application filed September 9, 1881. Term of patent 7 years.

To all whom it may concern:

Be it known that I, JOHN MARDER, a citizen of the United States, residing at Chicago, in the county of Cook and State of Illinois, have invented and produced a new and original Design for a Font of Printing-Type; and I do hereby declare that the following is a full, clear, and exact description of the invention, which will enable others skilled in the art to 5 10 15 20 25 which it appertains to make and use the same, reference being had to the accompanying printed copies of the font of type, making a part of this specification.

My invention consists of a new design for a font of printing-type, which I call "diagonal card black."

The font is composed of square black letters and figures having a heavy shade on the left-hand side and inlaid with light lines and with 20 25 heavy black lines extended diagonally across the face of the type. Narrow light spaces separate the left-hand shading and the front or

right-hand lines of the letters from the inlaying diagonal lines, all as shown in the accompanying copies of printed impressions of the type.

What I claim as new, and desire to secure by Letters Patent, is—

The new design for a font of printing-type called "diagonal card black," consisting of letters and figures having heavy shading on the left-hand side, and an inlaying of diagonal light lines and heavy black lines separated from the shading and from the front or right-hand lines by narrow light spaces, substantially as described and shown.

In testimony that I claim the foregoing as my own invention I affix my signature in presence of two witnesses.

JOHN MARDER.
